US0D1046651S

(12) **United States Design Patent** (10) **Patent No.:** **US D1,046,651 S**
(45) **Date of Patent:** **** Oct. 15, 2024**

(54) **TRACKING DEVICE MOUNT**

(71) Applicant: **Elevation Lab, Inc.**, Portland, OR (US)

(72) Inventors: **Casey Hopkins**, Portland, OR (US);
Jacob Hull, Portland, OR (US);
Mitchell T. Wilson, Portland, OR (US)

(73) Assignee: **Elevation Lab, Inc.**, Portland, OR (US)

(**) Term: **15 Years**

(21) Appl. No.: **29/878,984**

(22) Filed: **Jun. 29, 2023**

(51) LOC (14) Cl. **10-04**

(52) U.S. Cl.
USPC **D10/70; D10/104.1; D10/121**

(58) **Field of Classification Search**

(57) **CLAIM**

The ornamental design for a tracking device mount as shown and described.

DESCRIPTION

FIG. 1 is a top, right, front isometric view of a tracking device mount showing the new design;

FIG. 2 is a bottom, left, rear perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

The tracking device mount also may be referred to as a tracker mount, a tracker housing, a tracking device housing, a tracking mount pin, and/or a tracker pin. The broken lines represent portions of the tracking device mount that form no part of the claimed design.

1 Claim, 6 Drawing Sheets
